DOOR LOCK

Leland H. Fisler, New Britain, Conn., assignor to The American Hardware Corporation, New Britain, Conn., a corporation of Connecticut

Application July 19, 1952, Serial No. 299,807

11 Claims. (Cl. 70—210)

This invention relates to a door lock and more particularly to a door lock of the "cylindrical" type having an emergency release for unlocking the lock mechanism when the outer operating knob is dogged against operation.

Such locks, when used on the doors of bedrooms and bathrooms, are usually provided with both a dogging bar which is operable, by means projecting from the inner door knob, to dog the outer knob against operation, and with means actuated by the latch bolt to cause release of the dogging bar from its dogging position when the door is moved into closed position.

The invention, as illustrated herein, is embodied in the cylindrical door latch operating mechanism disclosed in Patent No. 2,733,088 issued to Leland H. Fisler et al., January 31, 1956, which mechanism is provided with a dogging bar for dogging the outer knob against operation as clearly shown and described in my co-pending application, Serial No. 293,338, filed June 13, 1952, now Patent No. 2,724,607 dated November 22, 1955, of which this application is a continuation in part.

It has been found important to provide such locks with emergency release means which are operable through the outer knob to effect disengagement of the said dogging bar from dogging position and permit opening of the door in the event that the person within the room should be disabled as a result of sickness or accident.

In cylindrical locks heretofore produced, numerous parts have been required for the emergency release mechanism and special constructions, which have added substantially to the cost of manufacture of said locks, have been necessary to support said mechanism.

An object of this invention is to provide a cylindrical door lock having emergency release means which cooperate with the retractor of said lock in a novel manner to cause release of the dogging bar when it is held in dogging position by said retractor.

A further object of the invention is the provision of a cylindrical door lock having emergency release means therein which include a bar that can be urged into engagement with and move the retractor of the lock by means of cam means contained in said lock.

A still further object of the invention is the provision of an emergency release bar which is inserted into the spindle of a cylindrical door lock without requiring special structure in the spindle for its support.

Further objects and advantages of this invention will be more clearly understood from the following description and the accompanying drawings in which:

Fig. 1 is a plan view of the cylindrical door lock, partially in central horizontal section, illustrating the dogging bar in dogging position and the emergency release bar in normal position.

Fig. 2 is a cross-sectional view of said lock along line 2—2 of Fig. 1.

Fig. 3 is a similar view on line 3—3 of Fig. 1.

Fig. 4 is a front view of said lock, partially in central

2

vertical section, further illustrating the emergency release bar.

Fig. 5 is an end view of the outer spindle of the lock illustrating the manner in which the emergency release bar is supported therein.

Fig. 6 is a cross-sectional view, on line 6—6 of Fig. 4, illustrating the guide means for the emergency release bar.

Fig. 7 is a fragmentary plan view of the emergency release bar, with the spindle illustrated in dotted lines, showing the manner in which the bar is supported and guided therein.

Fig. 8 is a plan view of the lock, with parts in section, illustrating the manner in which the emergency release bar operates.

Fig. 9 is an isometric view of said emergency release bar.

Referring to the drawings, it will be noted that the cylindrical door lock disclosed therein is, with the exception of the emergency release bar, the same as that disclosed in my above mentioned Patent No. 2,724,607. For the purpose of clarity the entire mechanism will now be described.

The said door lock includes a casing, generally indicated at 5, which houses and supports the latch operating mechanism and includes an inner end plate 6 and an outer end plate 7 having integral tubular sleeves 8 and 9 extending therefrom respectively. The end portion of each of said sleeves 8 and 9 is of a reduced diameter.

A retractor guide 10 is secured between the end plates 6 and 7 and is in the form of a U-shaped member having upper and lower legs 11 and 12, respectively; the inner surfaces of which are provided with longitudinally extending grooves 13—13 for the reception of ball members 14 which support a retractor 15 in the retractor guide. The said ball members 14 are maintained in proper relative position by means of cages 16.

The retractor 15 is preferably formed from a single piece of sheet metal and includes an inner side 17 from which is bent an upper leg 18 and a lower leg 19. The rear portion of each of said legs 18 and 19 has an extension 20 and 21, respectively, which is bent inwardly, parallel to the side 17, to form the outer side of the retractor. The inner side 17 of the retractor is also provided with extensions which are bent perpendicularly to said side and extend across the retractor to provide rollback platforms 22—22 thereon. The extensions 20 and 21 forming the outer side of the retractor and the rollback platforms 22—22 are spaced apart to provide a horizontal opening 23 which extends through a portion of the inner side 17 of the retractor, as indicated at 23-a, for a purpose to be hereinafter described. The outer ends of the retractor legs 18 and 19 are provided with oppositely disposed fingers 24—24 which receive the slotted end of a retractor bar 25 that is secured to the latch bolt 26 of a conventional latch unit 27; said unit being fastened to the casing 5 in a manner well-known to those versed in the art.

The outer surfaces of the retractor legs 18 and 19 contain longitudinally extending grooves, similar to the grooves 13—13 in the retractor guide, for the reception of the balls 14 which provide anti-friction bearings for the retractor to facilitate its sliding movement in the retractor guide.

The retractor guide 10 carries a spring support 28 from which projects a pair of fingers that support and guide compression springs 29—29. The free ends of the springs 29—29 project into the retractor, between its inner and outer side portions, and engage ears 30—30 extending from the opposite sides 31—31 of a U-shaped guide member 32; said ears being supported against the rollback platforms 22—22 of the retractor. The sides 31—31 of the

guide member 32 extend across the retractor and are spaced apart a distance substantially equal to the width of the opening 23-23-a. It will be understood that the guide member 32 is retained in the retractor by the springs 29-29 and that the said springs urge the retractor outwardly into normal position.

The inner sleeve 8 and the outer sleeve 9 are each provided with bearing members 33-33 which fit within the sleeves, as illustrated in Figs. 1 to 4, and are prevented from rotating relatively thereto by means of a tab 34 which is bent inwardly from each of said sleeves and projects into a slot 35 extending the entire length of each of said bearings. The formation of the tabs 34 provides a slot 36 in the inner and outer sleeve 8 and 9, respectively, which is in alignment with the slot 35 in the bearings 33-33. Movement of each of the bearings longitudinally of its respective sleeve is prevented by means of a finger 37 which is bent inwardly from each of said sleeves into a notch formed in the edge of each of said bearings.

An inner tubular spindle 38 and an outer tubular spindle 39 are rotatably supported by the bearing 33 in the inner sleeve 8 and in the outer sleeve 9, respectively, to provide an inner and an outer actuator for the retractor. Each of said spindles 38 and 39 has a segmental portion 40 projecting therefrom into the casing 5 and the opposite edges of said segmental portions are bent outwardly to provide rollbacks 41-41 which engage the platforms 22-22 of the retractor to both limit the outward movement of the retractor by the springs 29, and cause retraction thereof when either of the spindles is rotated. The free end of each of said segmental portions 40 is upwardly inclined as at 42 to provide an abutment 43 between said rollbacks 41-41 for a purpose to be herein-after more fully described.

The spindles 38 and 39 contain a slot 44 which extends the entire length thereof and is normally in alignment with the slots 35 and 36 in its respective bearing member and sleeve.

The spindles 38 and 39 are rotatably retained within the mechanism and prevented from moving axially therein by means of annular thrust washers 45-45 in the manner clearly disclosed in the co-pending application of Frank J. McConnell, Serial No. 275,618, filed March 8, 1952.

An inner knob 46 and an outer knob 47 are carried on the spindles 38 and 39, respectively, and each knob has a shank 48 extending therefrom which telescopically receives its respective spindle and projects through the reduced portion of sleeve to provide a bearing for the outer end of the spindle as clearly illustrated in Figs. 1 and 4. Each shank portion has a projection thereon which extends into the slot 44 in the spindle to transmit rotation of the knob to the spindle.

In order to prevent removal of the said knobs from the spindles, there is provided in each spindle a suitable knob retainer 49 in the form of a semi-circular member having a tongue that projects through a slot in the spindle into a slot in the knob shank, as illustrated in Fig. 1 and as clearly described in the above-mentioned Patent No. 2,733,088, and in my United States Patent No. 2,739,006 dated March 20, 1956. Said retainer is biased into retaining position by means of a spring 51 which is secured within the spindle.

The entire mechanism above described is maintained in assembled position by a cup-shaped cover 52 which extends over the end plates 6 and 7 and has ears 53 thereon which are bent inwardly over the outer end plate 7 and thereby permanently secure the mechanism in assembled position.

It will be understood from the above description that rotation of the inner knob 46 or the outer knob 47 will rotate its respective spindle and, through the engagement of the rollbacks 41-41 with the platforms 22-22 of the retractor, cause retraction of said retractor to

withdraw the latch bolt from the conventional strike (not shown) to permit opening of the door.

The door lock further includes a dogging unit as fully disclosed in Figs. 9, 10, 11 and 13 of the drawings of my above mentioned Patent No. 2,724,607. The dogging bar 54, which is shown in dogging position, has a shank 54-a which extends axially through the spindle and to the outer end of which there is securely attached a pushbutton 55 that is slidably within the inner spindle 38. The said pushbutton and dogging bar are urged into normal undogging position by a spring, not shown, that is contained within the spindle and forms a part of the dogging unit as clearly shown in said Patent No. 2,724,607.

The dogging bar has a flat head portion 56 which extends through the open inner end of the spindle 38 and through the opening 23-23-a in the retractor to a position between the sides 31-31 of the guide member 32 carried by said retractor. The head portion 56 of the dogging bar has a dogging finger 57 extending therefrom which, when the bar is in normal undogging position, lies between the sides of the guide member 32. The front edge of the head portion 56 of the dogging bar has a flat 58 thereon which engages the inner wall of the spindle when the bar is in undogging position and an angularly disposed cam surface 59 which extends from the flat 58. The opposite edge of the dogging bar is provided with a cam surface 60 and a detent 61 which are disposed adjacent the edge 62 of the opening 23-a in the side 17 of the retractor.

When it is desired to dog the outer knob against operation, as shown in Fig. 1, the pushbutton 55 is pushed inwardly thereby causing longitudinal movement of the dogging bar 54 with respect to the spindle. As the said dogging bar moves towards the outer spindle, the cam surface 59 engages the abutment 43 on the segmental portion of the spindle 38 and rides upwardly on said abutment thereby biasing the head portion 56 of the dogging bar rearwardly, with respect to the casing 5, to cause entry of the locking finger 57 into the slots 44, 35 and 36 formed in the outer spindle, bearing and sleeve respectively.

It will be noted that, as the bar moves towards the outer spindle and rearwardly with respect to the casing, the cam surface 60 will engage the said edge 62 of the opening 23-a in the retractor and urge the retractor rearwardly until the detent 61 passes said edge and the retractor springs urge the retractor into normal position to thereby cause engagement of said detent portion 61 with the side 17 of the retractor to retain the dogging bar in dogging position as clearly illustrated in Fig. 1, wherein operation of the outer knob and spindle is prevented.

Should the retractor be forced inwardly, either by depression of the latch bolt, which is secured to the retractor in the conventional manner to cause retraction thereof by said bolt when the door is moved into closed position, or by operation of the inner spindle, the side portion 17 of the retractor will be carried rearwardly out of engagement with the detent portion 61 of the dogging bar and thereby permit the spring within the spindle 38 to return said bar and pushbutton to normal position.

The door lock above described functions in a manner which renders it particularly suited for use on doors requiring a lock that may be dogged against operation from the outside and in which said dogging means is released when the inner spindle is rotated or, in the event that said dogging means is accidentally moved to dogging position while the door is open, when the retractor is moved rearwardly by the latch bolt as the door is closed.

In order to transform said door lock into one which is suited for use on doors of bedrooms and bathrooms, wherein means are required to permit undogging of the outer spindle in cases of emergency, I have provided a simple and inexpensive emergency release means which are insertable into the outer spindle of the lock without requiring complete disassembly thereof.

Said emergency release means include an emergency

release bar 63 having a flat disc-shaped head portion 64 which is slidably supported within the spindle 39 and has a shank 65 extending perpendicularly therefrom with an offset portion 66 that is provided with laterally extending fingers 67—67 which are received in diametrically opposed guide slots 68—68 in said spindle 39. Said slots 68—68 extend from slots 69—69 which are formed in said spindle for the reception of the pin tumbler chamber of a cylinder lock which is insertable into the spindle when required.

The slots 68—68 are offset relatively to the slots 69—69 to provide abutment shoulders 70, at the outer end of said slots 68—68, which are engaged by the arms 67—67 to retain the emergency release bar within the spindle. When the emergency release bar is in normal position, as illustrated in Figs. 1, 4 and 7, the arms 67—67 are held against said abutment shoulders by a compression spring 71 which surrounds the shank 65 and has one end abutting the said arms. The opposite end of said compression spring 71 rests in a cup-shaped member 72 that is carried within said spindle and supported against an ear, not shown, which is bent inwardly from the side of the spindle and pivotally supports the knob retainer 49. Said cup-shaped member is identical to the cup-shaped members employed for supporting the springs in other lock functions such as described in said Patent No. 2,724,607.

The shank of the emergency release bar 63 projects through an opening in the bottom wall of the cup-shaped member and has an angularly disposed end portion 73 which extends into engagement with the inner wall of the spindle 39 to provide a support for the inner end of said emergency release bar. Said inner end has an oppositely inclined portion that is bifurcated to provide spaced fingers 74—74 thereon that are normally disposed within the segmental portion 40 of the spindle 39 and adjacent the rollback platforms 22—22. The forward surface of said spaced fingers is tapered to provide a cam surface 75—75 on each of them.

The emergency release bar is inserted into the outer spindle by first removing the outer rose, not shown, which is threaded to the sleeve 9 and conceals the locking mechanism and knob retainer as described in said Patent No. 2,733,088. The knob retainer 49 is thereby rendered accessible and may be depressed with a suitable tool to permit removal of the outer knob 47 from the spindle 39. The assembled emergency release bar, cup-shaped spring support 72 and spring 71 are then inserted into said spindle to the position illustrated in Fig. 1; the said spindle being opened slightly by inserting a suitable tool into the slot 44 therein to allow the arms 67—67 to pass therethrough into the slots 68—68. The outer rose and knob are then replaced.

When the dogging bar 54 is in dogging position, operation of the outer spindle and knob is prevented since the dogging finger 57 is disposed within the slots in the outer spindle, bearing and sleeve respectively and, as above noted, the said bar is maintained in dogging position through engagement of the detent 61 thereon with the side of the retractor. If it is desired to release the dogging bar 54 from dogging position from the exterior of the door, a suitable tool 76 is inserted through a hole 77, which is provided in the outer knob, and into engagement with the head 64 of the emergency release bar. The said bar is then pushed inwardly, by means of the tool 76, thereby causing the cam surfaces 75—75 on the fingers 74—74 to ride upwardly on the abutment 43 of the segmental portion 40 on the spindle and into engagement with the rollback platforms 22—22 of the retractor. Further inward movement of the emergency release bar will cause the said bar to move the retractor rearwardly until the edge 62 of the opening 23-a in the side 17 of the retractor is disengaged from the detent 61 on the dogging bar as illustrated in Fig. 8. The spring contained within the inner spindle 38, which controls the dogging bar 54, will, upon release of said detent, urge said bar

and pushbutton into normal undogging position to permit undogging of the outer spindle and knob.

It will be noted, in Fig. 8, that the spaced fingers 74—74 on the end of the emergency release bar straddle the dogging bar to prevent interference therebetween as said emergency release bar is moved inwardly by the tool 76. As soon as the undogging of the outer spindle and knob is accomplished, the tool 76 is removed and the spring 71 will return the emergency release bar to normal position so that the door may be opened by rotation of the outer knob and spindle.

It will be understood from the above description that my invention provides a simple and inexpensive emergency release mechanism for a cylindrical door lock which is easily insertable into said lock and does not require the use of special parts or other mechanism for its support and operation.

I claim:

1. A door lock comprising a casing, a retractor for a latch bolt mounted in said casing, an inner and an outer actuator carried by said casing for causing retraction of the retractor dogging means associated with the inner actuator for dogging the outer actuator against operation; said dogging means being retained in dogging position by engagement with a portion of said retractor, a longitudinally movable bar associated with the outer actuator and adapted to be moved relatively thereto, and means engageable by said bar upon movement thereof for urging it into engagement with the retractor for causing retraction thereof to effect disengagement of said dogging means from the retractor.
2. A door lock comprising a casing, a retractor for a latch bolt mounted in said casing, an inner and an outer actuator carried by said casing for causing retraction of the retractor, dogging means associated with the inner actuator for dogging the outer actuator against operation; said dogging means being retained in dogging position by engagement with a portion of said retractor, a movable bar associated with the outer actuator and adapted to be moved relatively thereto, and cooperative cam means operable upon movement of the bar to urge it into engagement with the retractor for causing retraction thereof to effect disengagement of said dogging means from the retractor.
3. A door lock comprising a casing, a retractor for a latch bolt mounted in said casing, an inner and an outer actuator carried by said casing for causing retraction of the retractor, dogging means associated with the inner actuator for dogging the outer actuator against operation; said dogging means being retained in dogging position by engagement with a portion of said retractor, an abutment, a movable bar associated with the outer actuator and adapted to be moved inwardly relatively thereto, and cam means on said bar engageable with the said abutment as the bar is moved inwardly for biasing said bar into engagement with the retractor to cause retraction thereof to effect disengagement of said dogging means from the retractor.
4. A door lock comprising a casing, a retractor for a latch bolt mounted in said casing, an inner and an outer tubular spindle rotatably mounted in said casing, rollback means on each of said spindles for actuating the retractor, dogging means carried within the inner spindle for dogging the outer spindle against operation; said dogging means being retained in dogging position by engagement with a portion of said retractor, a longitudinally movable bar carried within the outer spindle and adapted to be moved inwardly therein, and cam means on said bar engageable with said retractor, upon inward movement of the bar, to cause retraction thereof and disengagement of said dogging means from the retractor.
5. A door lock comprising a casing, a retractor for a latch bolt mounted in said casing, an inner and an outer tubular spindle rotatably mounted in said casing, rollback means on each of said spindles for actuating the retrac-

tor, dogging means carried within the inner spindle for dogging the outer spindle against operation; said dogging means being retained in dogging position by engagement with a portion of said retractor, a longitudinally movable bar carried within the outer spindle, cam means within said outer spindle, and means for moving said bar into engagement with said cam means whereby said bar is biased into engagement with said retractor to cause retraction thereof and disengagement of said dogging means from said retractor.

6. A door lock comprising a casing, a retractor for a latch bolt mounted in said casing, an inner and an outer tubular spindle rotatably mounted in said casing, dogging means carried within the inner spindle and movable into position to dog the outer spindle against operation, said dogging means being retained in dogging position by engagement thereof with a portion of said retractor, a longitudinally movable bar carried within the outer spindle, means for moving said bar inwardly relatively to said spindle, an abutment in said outer spindle, and cam means on said bar engageable with said abutment upon inward movement of said bar whereby said bar is biased into engagement with said retractor to cause rearward movement thereof with respect to the casing to effect disengagement of said dogging means from the retractor.

7. A door lock comprising a casing, a retractor for a latch bolt mounted in said casing, an inner and an outer tubular spindle rotatably mounted in said casing, rollback means associated with the inner spindle for actuating the retractor, a segmental portion projecting from the outer spindle into the casing; the opposite edges of said segmental portion providing rollbacks for actuating the retractor, dogging means carried within the inner spindle and movable into dogging position wherein the outer spindle is dogged against operation; said dogging means being retained in dogging position by engagement with said retractor, a longitudinally movable bar carried within the outer spindle, means for moving said bar in said spindle, a cam surface on the end of said bar, and an abutment on said segmental portion; said cam surface being adapted to ride upwardly on said abutment, upon movement of the bar, whereby said bar is biased into engagement with the retractor to cause retraction thereof and disengagement of said dogging means from the retractor.

8. A door lock comprising a casing, a retractor for a latch bolt mounted in said casing, an inner and an outer tubular spindle rotatably mounted in said casing and each having a knob thereon, rollback means on each of said spindles for actuating the retractor, dogging means carried within the inner spindle and movable into dogging position wherein the outer spindle is dogged against operation, said dogging means being retained in position by engagement with a portion of said retractor, a longitudinally movable bar carried within the outer spindle, spring means

urging said bar outwardly with respect to the outer spindle and into its normal position, abutment means in the outer spindle for limiting outward movement of said bar by said spring means, said bar being accessible for actuation thereof through an opening in the knob on the outer spindle, and cooperative cam means on said bar and in said outer spindle for biasing the bar upon actuation thereof into engagement with the retractor to cause retraction thereof whereby said dogging means is disengaged from said retractor.

9. A door lock is set forth in claim 8 wherein said longitudinally movable bar is provided with a head portion slidably mounted within said outer spindle adjacent the opening in said knob and said head portion is engageable with a tool to cause longitudinal movement of the bar.

10. A door lock as set forth in claim 8 wherein the said longitudinally movable bar is provided with oppositely extending transverse arms which project through oppositely disposed slots in said outer spindle to provide a guide for said bar and the ends of said slots provide said abutment means in the outer spindle to limit outward movement of said bar by said spring means.

11. A door lock comprising a casing, a retractor for a latch bolt slidably mounted in said casing and having rollback platforms, an inner and an outer tubular spindle rotatably mounted in said casing, rollback means associated with the inner spindle for actuating the retractor, a segmental portion extending from the outer spindle into the casing, the opposite edges of said segmental portion providing rollbacks for actuating the retractor, dogging means carried by the inner spindle for dogging the outer spindle against operation; said dogging means being retained in dogging position by engagement with a portion of said retractor, a longitudinally movable release bar carried within said outer spindle; the inner end portion of said bar being disposed in said segmental portion adjacent the rollback platforms of the retractor and being provided with a cam surface, an abutment on said segmental portion between said rollbacks, said bar being accessible through an opening in the knob on the outer spindle to permit movement thereof whereby the end portion of said bar is biased into engagement with said retractor by the cooperative action of said cam surface and abutment to cause retraction thereof and disengagement of said dogging means.
